UNITED STATES PATENT OFFICE.

ETHELBERT M. FRASER, OF SAN FRANCISCO, CALIFORNIA.

ELEVATOR.

SPECIFICATION forming part of Letters Patent No. 631,710, dated August 22, 1899.

Application filed June 19, 1899. Serial No. 721,052. (No model.)

To all whom it may concern:

Be it known that I, ETHELBERT M. FRASER, a citizen of the United States, residing in the city and county of San Francisco, State of California, have invented an Improvement in 5 Elevators; and I hereby declare the following to be a full, clear, and exact description of the same.

My invention relates to an improvement in 10 elevators or hoisting-machines such as are used for passengers or freight, and especially to hoisting-machines of that class which are well illustrated in Patent No. 610,481, dated September 6, 1888.

15 My present invention is designed to provide a means for automatically maintaining any desired tension upon the endless traveling ropes or cables by which the raising and lowering of the cage and connected parts are at- 20 tended.

It also comprises details of construction, which will be more fully explained by reference to the accompanying drawings, in which—

25 Figure 1 is a view illustrating one form of my device. Fig. 2 shows the parts separated for the clearer understanding of the operation.

The height or distance through which the elevator-cage and counterbalance-weights 30 and connected parts are operated are necessarily shortened to comply with the limitations of the drawings; but it will be understood that these distances represent the heights of any building or wells or shafts in which the 35 apparatus is designed to operate.

A is a car or equivalent device to be hoisted. B is the rope or cable passing over a pulley C in the upper part of the shaft or space through which the cage is designed to move, 40 and D is a counterweight with which the opposite end of the rope or cable is connected. This counterweight is suitably proportioned to the weight of the car and to a second counterweight to be hereinafter described. These 45 weights act in conjunction to balance the car and are so proportioned to each other as to divide the strain on the transmitting-ropes G G, as may be desired. Either weight may be the heavier, the effect on the car being the 50 same. When the counterweight is drawn downward, the car is drawn upward. When

the counterweight is drawn upward, it correspondingly allows the car to descend.

The mechanism by which the car is operated consists of two independently-driven 55 pulleys E and F and an endless rope or cable G, passing over said pulleys, thence in one direction over an idle pulley H, connected with the counterweight D, and in the other direction over an idle pulley I, connected with a 60 movable frame J. This frame has a rope K passing over a pulley C' in the upper part of the shaft, well, or hoistway, thence down to a counterweight L, which serves indirectly to maintain the tension of the ropes G. In 65 practice these ropes G pass about the grooved pulleys, and may be as many in number as are required for the purpose.

The general operation of the apparatus is, as fully stated in my former patents, produced 70 by the relatively different rates of circumferential speed of the driving-pulleys, and these pulleys E and F act through the ropes G and the connected parts to either raise or lower the car.

75 It will be understood that the car, the counterweight, and the movable framework J are for convenience made to travel in suitable guides, which maintain them in their proper lines of travel; but these are omitted in the 80 drawings in order to show the special features of the invention clearly.

It will thus be seen that by means of the counterweight L an independent and indirect tension is constantly maintained upon the 85 ropes G, and that no other special means for adjusting this tension is needed or any attention to the device.

As shown in Fig. 2, the cage and the counterbalances D and L are separated and independent of each other; but for convenience in operating and to economize space in which the parts move I have shown a construction in Fig. 1 in which the frames D' upon which the counterweight of the car is carried serve 90 as guides for the independently-movable counterweight L. These guides D' are of sufficient length to allow for all necessary movement of the weight L. This weight in either case then acts through the movable frame J 95 and its pulley I upon the ropes G, which pass around the drivers E and F, and thence to 100

the pulley H upon the counterweight D, and through this is in direct connection with the car itself.

Having thus described my invention, what 5 I claim as new, and desire to secure by Letters Patent, is—

1. The combination with independently-operated pulleys, an endless cable thereon, and a cage connected to and operated by said 10 endless cable, of an automatically-operating tension device whereby the tension of said cable is constantly maintained.

2. In an elevator, a car and counterweight therefor, and independently-operating driving-pulleys with an endless rope or cable passing around them connecting with and around a pulley upon the counterweight, and also around a pulley upon an independently-movable frame, and an independently-actuated 20 counterweight connecting with said frame.

3. In an elevator, the combination with a car or cage, a counterweight and a rope or cable passing over a pulley and connecting the weight and car, of independently-operated 25 pulleys with an endless cable driven thereby

passing at one end around a pulley connected with the cage-counterweight, and at the other around a pulley connected with a frame, and a second counterweight connected with said frame by rope or cable passing over a second 30 pulley in the upper part of the hoistway.

4. A hoisting car or cage, a rope passing from the car over a pulley, a counterweight with which the opposite end of the rope connects, guides upon said counterweight, a second 35 counterweight slideable upon said guides, a rope passing from said second counterweight over a pulley and thence to a movable frame, in combination with independently-actuated driving-pulleys, an endless rope or 40 cable thereon and pulleys upon the main counterweight and the frame around which said rope or cable passes.

In witness whereof I have hereunto set my hand.

ETHELBERT M. FRASER.
